REMOTE CONTROLLED SHOOTING
GALLERY

Joseph A. McKenzie, Rapid City, S. Dak.

Application August 14, 1950, Serial No. 179,291

11 Claims. (Cl. 273—105.6)

1

The present invention relates to improvements in shooting galleries, and more particularly to the type of shooting gallery where means are provided for automatically supplying targets to firing position and removing the targets from the position to a conveyor means whereby the targets may be conveyed to a point outside the firing line.

An object of the present invention is to provide a novel selectively actuatable means whereby individual targets may be fed at preselected times to a firing position.

A further object of the present invention is to provide a novel arrangement whereby the targets may be positioned on a carrier means and are moved by gravity from a first position for receiving the targets and to a second position for holding the same in target-firing position.

Still another object of the present invention is to provide a novel target holder bin whereby a plurality of targets may be held for feeding one at a time to the carrier means.

A further object of the present invention resides in the provision of means for providing synchronizing movement between the target feed mechanism and the target carrying mechanism.

Still another object of the present invention is to provide a novel construction for a pair of target units whereby the gallery may be easily prefabricated, shipped and erected, and which gallery is adapted for use in various sized buildings.

Another object of the present invention is to provide a remote control means whereby targets may be interchanged with new targets without leaving the firing line.

Still another object of the present invention is to provide a remote control means whereby a pair of targets may be simultaneously interchanged for new targets for competitive firing.

Various other objects and advantages will be apparent from the detailed description to follow. In the description as well as in the claims, parts are at times identified by specific names for convenience, but such nomenclature is intended to be as generic in its application to analogous parts as the prior art will permit. My invention is clearly defined in the appended claims.

The best form in which I have contemplated applying my invention is illustrated in the accompanying drawings, wherein:

Figure 1 is a rear elevational view showing the assembly of a pair of target units and the conveyor mechanism;

Figure 2 is a vertical transverse sectional view taken substantially along the plane of line 2—2 of Figure 1;

Figure 3 is a vertical transverse sectional view taken substantially along the plane of line 3—3 of Figure 1;

Figure 4 is a horizontal sectional view taken substantially along the line 4—4 of Figure 3;

Figure 5 is a detail view showing a section of

2

the endless link-type carrier chain with one of the stop pins projecting therefrom;

Figure 6 is a perspective view showing the tripper bar employed with the present invention;

Figure 7 is a detail view of the end of the tripper bar showing the tripper dog pivotally mounted thereon;

Figure 8 is a view of one form of target holder;

Figure 9 is a vertical sectional view of the target holder of Figure 8;

Figure 10 is an exploded view of a second form of target holder;

Figure 11 is a view of the holder of Figure 10 in assembled relation;

Figure 12 is a perspective detail view of one of the rings employed in conjunction with the holder of Figure 10;

Figure 13 shows a form of target employed with the shooting gallery of the present invention; and

Figure 14 is a view disclosing the "Bulley" score card by means of which the score obtained on the targets of Figure 13 may be tabulated.

Referring more particularly to the drawings, 25 wherein like numerals designate like parts throughout, the numeral 10 designates generally the target rack means, the numeral 12 designates generally the target feed mechanism, the numeral 14 designates generally a target and target holder 30 means, the numeral 16 designates generally the solenoid actuating means whereby the target feed mechanism 12 may be actuated, the numeral 18 designates generally the carrier means, the numeral 20 designates generally the conveyor means by which the targets may be conveyed from the line of fire to an outside position and the numeral 22 designates a form of score card.

The means for supporting the target feeding and carrying mechanism includes a pair of end standards 24, a center standard 26, and cross-bars 28. The cross-bars 28 are secured at their ends to the standard 24 to provide a rigid rectangular frame, with the center standard 26 serving as rigidifying means.

45 The target rack means 10 includes a pair of angulated straps 30 which are disposed in inclined position with respect to the horizontal and have their lower ends secured to the upstanding pairs of bars 34 by means of the screws 32. In the form shown in Figure 1, I have pro-

50 vided two pair of upstanding bars 34 whereby a pair of target racks 10 may be mounted in the supporting framework. The standard 24 and upper cross-bar 28 have projecting forwardly therefrom a pair of support struts 36. Disposed below the supporting struts 36 is a protective steel sheeting 38 which is in parallel relation to the angulated straps 30 and has its lower end secured to the standards 24 and its upper end supported

55 by the bars 40 which are secured at their upper ends to the supporting struts 36. A target supply 60

door 42 is hingedly secured at 44 to the upper end of the protective sheeting 38.

The target means 14, as shown in its preferred embodiment in Figures 3 and 8, includes a tubular element 46 which is provided with an open-ended slot 48. The individual tubular elements 46 may be provided with individual targets 50 having their upper edge portions folded over as at 52, whereby the targets 50 may be inserted into the slots 48 for retention thereby. The open end of the tubular element 46 and slot 48 is closed by means of the plug 54. It will readily be seen that a plurality of target holders and targets 14 may be inserted through the door 42 and onto the angulated straps 30.

The target feeding means 12, as best seen in Figures 3 and 4, includes a target feed sprocket 56 which is mounted for rotation on the shaft 58, which is in turn rotatably disposed within the bearing 60 in each of the upstanding bars 34. The sprocket 56 is provided with a boss 62, with a pin 64 extending therethrough whereby the sprocket may be securely positioned on the shaft 58. Secured to one side of the target feed sprocket 56 is a dog gear 66 which is mounted for rotation with the shaft 58. It will be seen that as the dog gear 66 is rotated, the notches 68 of the sprocket 56 will engage the individual target holders and targets 14 for movement along the angulated straps 30.

The means whereby the dog gear 66 may be selectively actuated is best shown in Figure 4 and includes a solenoid 70 of conventional form having electrical conductors 72 which are in turn connected to a switch at the firing line for actuation thereby. The solenoid 70 is mounted within a casing 74 which is supported by means of the angulated member 76 which is secured by screws 78 to one of the supporting bars 34. The supporting bars 34 upon which the solenoids 70 are mounted are provided with openings 80 therethrough. Levers 82 are pivotally mounted on pins 84 in the supporting bars 34 and have one end connected to the plunger 86 of the solenoid 70 by means of the adjustable connector 88. The other end of the lever 82 is connected to the bifurcations 90 of the tripper bar 92, which is best shown in Figure 6. The tripper bar 92 is reciprocably mounted on the plate 94 which is provided with guide elements 96 and which is secured to the standard 34 by means of screws 98. The tripper bar 92 is provided with a stop projection 100, for a purpose to be hereinafter described, and is apertured at 102. As best seen in Figures 3 and 7, a tripper dog 104 is pivotally mounted on a pin 106 in the aperture 102. The tripper dog 104 is provided with a recess 108 which is adapted to receive the end of the tripper bar 92 having the aperture 102 and in which is mounted an angulated strap spring 110 whereby the tripper dog 104 is held in the position shown in Figure 7. When the solenoid 70 is actuated, the plunger 86 will move to the left, in Figure 4, pivoting the lever 82 so that the tripper bar 92 moves to the right, and as seen in Figure 3, the tripper dog 104 having a pointed portion 112 which is adapted to engage a tooth of the dog gear 66 for effecting rotation thereof in conjunction with the sprocket 56.

A resilient means 114 is attached at one end to the plate 94 at 116 and has its other end attached to the tripper bar 92 by means of the lateral extension 118 secured thereto for normally urging the tripper bar 92 to disengaged position.

The carrier means for the target holders and targets includes a pair of sprockets 120 which are mounted one above the other within the bearings 122 which are in turn seated within the recesses 124 of the bracket 126, the brackets 126 being secured by means of lugs 128 to the standards 34. As seen in Figure 1, there are two sets of sprockets 120, secured to the two sets of standards 34, whereby endless link type chain carriers 130 may be freely rotatably carried by each pair of sprockets 120. The chain carrier 130, shown in detail in Figure 5, is provided with a plurality of outwardly projecting pins 32 which act as stops when engaged with the stop projection 100 on the tripper bar 92. As seen in Figure 3, the carrier chain 130 is also provided with a plurality of target holding elements 134 which are formed with arcuated portions 136 for receiving the tubular target holders 46 and an arcuated portion 138 which is pivotally mounted to the chain 130, as at 140. Second arcuated elements 142 are pivotally mounted to the chain 130 at 144 and to the intermediate portion of the target carrier element 134, as at 146.

The target rack means 10 is provided with a stop means which may include either one or a pair of pivotally mounted stop members 148 which are pivotally mounted within the bifurcations 150 integrally formed on the angulated straps 30 of the target rack. A resilient means 152 has an end portion 154 engaging a lower edge of the stop member 148, has an intermediate portion wound around the pin 156, upon which the stop member 148 is mounted, and has an end portion 154 which bears against the angulated portion 31 of the angulated strap 30. The stop member 148 is provided with an upwardly extending projection 156 which is adapted to stop the target holders as they are released from the sprocket 56. It should be here noted that the stop members 148 are in vertical alignment with the carrier elements 134 of the carrier means 18. It will therefore be readily seen that when the solenoid is actuated, the tripper bar 92 will move to the right, releasing the pin 132 from the stop projection 100, and the weight of the target and target holder in the holding element 134 will cause the chain carrier 130 to rotate with the sprockets 120, and as one of the empty elements 134 engages the stop member 148, it will be pivoted downwardly, releasing a holder retained thereby and the holder will drop into the arcuated portion 136 of the element 134. The chain carrier 130 will then move downwardly by force of gravity until another pin 132 engages the stop projection 100 when it is returned to its normal position with the solenoid de-actuated.

The conveyor means 20 is supported by means of the framework 160 which includes outer upstanding bars 162 which are secured in spaced relation to the standards 24 by means of the cross-bars 164. A plurality of rollers 166 are rotatably supported at one end by means of the straps 170 which are secured to the guide walls and protecting plates 172 which extend longitudinally of the conveyor means. The other ends of the rollers 166 are supported by means of the longitudinally extending member 174 which is provided at its upper edge with the protective guide plate 176. A motor stand 178 is mounted at one end of the frame 160 and an electric motor 180 is securely positioned thereon. A sheave 182 is rotatably disposed between a pair of plates 184 secured to the end standard 24, and a belt 186 operatively connects the sheave 182 to the electric

motor 180. An idler roller 188 is mounted in the framework 160 by means of the projecting struts 190, and an endless belt 192 is passed over the rollers 166 and idler 188, whereby the targets dropping from the elements 134 may be conveyed to a position outside of the firing line. As seen in Figure 2, a diverting plate 193 may be supported between the standards 34 for deflecting the targets which are dropped from the carrier means onto the conveyor 20.

A second form of target holder is shown in Figure 10 and includes a pair of complementary target holding elements 194 and 196. The element 194 is provided with a plurality of recesses 198 and the element 196 is provided with a plurality of projecting pins 200 and a recessed portion 204 for receiving the upper edge portion of a target. The end portions of the elements 194 and 196 are of reduced cross section and are adapted to receive the rings 206 when the elements 194 and 196 are in clamped relation on a target. It will readily be seen that a target may be positioned within the recess 204 with the pins 200 extending therethrough and the elements 194 held to the element 196 by means of the rings 206.

An examination of Figure 13 will disclose the form of target to be employed with the present invention. With this form, the competitor fires the first shot at the top bull of the target, and if a "10" is scored, he gains the right to fire the two remaining shots of the three allowed at the top bull. If the first shot scores a number which is less than ten, the competitor is compelled to fire a second shot at the bottom bull in an attempt to score a number that will give him a total of ten or more for the two shots. If the first two shots total ten or more, he regains the right to fire the third shot at the top bull.

In the bullet score card, as shown in Figure 14, the blocks 208 are for recording the scores of the three shots allotted for each of the ten numbered columns. Block 210 is for recording the total of the three shots in each of the ten numbered columns. Block 212 is for recording the total of the last column fired and the totals of all previously fired columns. The competitor gains the right to fire an additional three shots to be scored in the last column on the score card if he scores all three "tens" in column ten only. The competitors' names appear in the blocks 214.

It should be understood that other forms of targets and score cards may be employed equally well with the structure of my invention and I do not wish to be limited thereby.

Some changes may be made in the construction and arrangement of the parts of my device without departing from the real spirit and purpose of my invention.

Having described the invention, what is claimed as new is:

1. A target feed mechanism comprising a target rack means, a plurality of target holders in said rack means and holding a plurality of individual targets, selectively actuatable means for feeding one of said target holders from said rack to a second position, stop means at said second position on said rack for retaining said holders in said second position, an endless target carrier means, means supporting said endless carrier means for free movement, said endless carrier means being engageable with said stop means for disengaging said holders from said second position and being adapted to receive said holders to hold the targets in firing position.

2. A target feed mechanism comprising a target rack means, a plurality of target holders in said rack means and holding a plurality of individual targets, selectively actuatable means for feeding one of said target holders from said rack to a second position, stop means at said second position on said rack for retaining said holders in said second position, an endless target carrier means, means supporting said endless carrier means for free movement, said endless carrier means being engageable with said stop means for disengaging said holders from said second position and being adapted to receive said holders to hold the targets in firing position, said carrier means including a plurality of carrier elements and a plurality of carrier pins, said pins being adapted to engage said selectively actuatable means for intermittently stopping said carrier means in preselected positions.

3. A target feed mechanism comprising a target rack means, a plurality of target holders in said rack means and holding a plurality of individual targets, selectively actuatable means for feeding one of said target holders from said rack to a second position, stop means at said second position on said rack for retaining said holders in said second position, an endless target carrier means, means supporting said endless carrier means for free movement, said endless carrier means being engageable with said stop means for disengaging said holders from said second position and being adapted to receive said holders to hold the targets in firing position, and conveyor means disposed with a portion beneath said firing position for receiving a target after firing whereby the target may be conveyed to a point without the firing line.

4. A target feed mechanism comprising a target rack means, a plurality of target holders in said rack means and holding a plurality of individual targets, selectively actuatable means for feeding one of said target holders from said rack to a second position, stop means at said second position on said rack for retaining said holders in said second position, an endless target carrier means, means supporting said endless carrier means for free movement, said endless carrier means being engageable with said stop means for disengaging said holders from said second position and being adapted to receive said holders to hold the targets in firing position, said target rack means including a plurality of angulated straps supported by a stand means and in inclined position, the ends of said target holders being slidably supported by said straps.

5. A target feed mechanism comprising a target rack means, a plurality of target holders in said rack means and holding a plurality of individual targets, selectively actuatable means for feeding one of said target holders from said rack to a second position, stop means at said second position on said rack for retaining said holders in said second position, an endless target carrier means, means supporting said endless carrier means for free movement, said endless carrier means being engageable with said stop means for disengaging said holders from said second position and being adapted to receive said holders to hold the targets in firing position, said selectively actuatable means including a target feed sprocket, the notches on the periphery of said sprocket adapted to engage the end of a target holder for moving the same.

6. A target feed mechanism comprising a target rack means, a plurality of target holders in

said rack means and holding a plurality of individual targets, selectively actuatable means for feeding one of said target holders from said rack to a second position, stop means at said second position on said rack for retaining said holders in said second position, an endless target carrier means, means supporting said endless carrier means for free movement, said endless carrier means being engageable with said stop means for disengaging said holders from said second position and being adapted to receive said holders to hold the targets in firing position, said selectively actuatable means including a target feed sprocket, the notches on the periphery of said sprocket adapted to engage the end of a target holder for moving the same, a dog gear rotatable with said sprocket, means for intermittently actuating said dog gear for limited rotation thereof.

7. A target feed mechanism comprising a target rack means, a plurality of target holders in said rack means and holding a plurality of individual targets, selectively actuatable means for feeding one of said target holders from said rack to a second position, stop means at said second position on said rack for retaining said holders in said second position, an endless target carrier means, means supporting said endless carrier means for free movement, said endless carrier means being engageable with said stop means for disengaging said holders from said second position and being adapted to receive said holders to hold the targets in firing position, said selectively actuatable means including a target feed sprocket, the notches on the periphery of said sprocket adapted to engage the end of a target holder for moving the same, a dog gear rotatable with said sprocket, means for intermittently actuating said dog gear for limited rotation thereof, said last-named means including a tripper bar reciprocably mounted in juxtaposition to said dog gear, a tripper dog on one end of said bar for sequential engagement with the teeth of said dog gear, a stop projection on said tripper bar, one of said pins being adapted to engage said stop projection for holding the carrier means from movement, movement of said tripper bar adapted to disengage said projection from beneath said pin whereby gravity will move said carrier means and target to target-unloading position.

8. A target feed mechanism comprising a target rack means, a plurality of target holders in said rack means and holding a plurality of individual targets, selectively actuatable means for feeding one of said target holders from said rack to a second position, stop means at said second position on said rack for retaining said holders in said second position, an endless target carrier means, means supporting said endless carrier means for free movement, said endless carrier means being engageable with said stop means for disengaging said holders from said second position and being adapted to receive said holders to hold the targets in firing position, said selectively actuatable means including a target feed sprocket, the notches on the periphery of said sprocket adapted to engage the end of a target holder for moving the same, a dog gear rotatable with said sprocket, means for intermittently actuating said dog gear for limited rotation thereof, said last-named means including a tripper bar reciprocably mounted in juxtaposition to said dog gear, a tripper dog on one end of said bar for sequential engagement with the teeth of said dog gear, solenoid means for urging said tripper bar for actuating said dog gear, and resilient means for urging said tripper bar in the opposite direction.

9. A target feed mechanism comprising a target rack means, a plurality of target holders in said rack means and holding a plurality of individual targets, selectively actuatable means for feeding

one of said target holders from said rack to a second position, stop means at said second position on said rack for retaining said holders in said second position, an endless target carrier means, means supporting said endless carrier means for free movement, said endless carrier means being engageable with said stop means for disengaging said holders from said second position and being adapted to receive said holders to hold the targets in firing position, said carrier means including a plurality of carrier elements and a plurality of carrier pins, said selectively actuatable means including a target feed sprocket, the notches on the periphery of said sprocket adapted to engage the end of a target holder for moving the same, a dog gear rotatable with said sprocket, means for intermittently actuating said dog gear for limited rotation thereof, said last-named means including a tripper bar reciprocably mounted in juxtaposition to said dog gear, a tripper dog on one end of said bar for sequential engagement with the teeth of said dog gear, a stop projection on said tripper bar, one of said pins being adapted to engage said stop projection for holding the carrier means from movement, movement of said tripper bar adapted to disengage said projection from beneath said pin whereby gravity will move said carrier means and target to target-unloading position.

10. A target feed mechanism comprising a target rack means, a plurality of target holders in said rack means and holding a plurality of individual targets, selectively actuatable means for feeding one of said target holders from said rack to a second position, stop means at said second position on said rack for retaining said holders in said second position, an endless target carrier means, means supporting said endless carrier means for free movement, said endless carrier means being engageable with said stop means for disengaging said holders from said second position and being adapted to receive said holders to hold the targets in firing position, said target holders including tubular members having longitudinal target receiving slots therein.

11. A target feed mechanism comprising a target rack means, a plurality of target holders in said rack means and holding a plurality of individual targets, selectively actuatable means for feeding one of said target holders from said rack to a second position, stop means at said second position on said rack for retaining said holders in said second position, an endless target carrier means, means supporting said endless carrier means for free movement, said endless carrier means being engageable with said stop means for disengaging said holders from said second position and being adapted to receive said holders to hold the targets in firing position, said target holders comprising a pair of complementary elements, securing pins on one of said elements whereby an edge portion of said targets may be positioned between said complementary elements and secured therebetween.

JOSEPH A. MCKENZIE.
